UNITED STATES PATENT OFFICE.

WILLIAM C. MURDOCK, OF DETROIT, MICHIGAN, ASSIGNOR TO ELLSWORTH S. BRYANT, OF DETROIT, MICHIGAN.

DESIGN FOR A CASING FOR VENDING-MACHINES.

SPECIFICATION forming part of Design No. 35,872, dated April 15, 1902.

Application filed February 1, 1902. Serial No. 92,208. Term of patent 7 years.

To all whom it may concern:

Be it known that I, WILLIAM C. MURDOCK, a citizen of the United States, residing at Detroit, in the county of Wayne and State of Michigan, have invented and produced a certain new and original Design for a Casing for Vending-Machines, of which the following is a specification, reference being had therein to the accompanying drawings, in which—

10 Figure 1 is a perspective view of the casing. Fig. 2 is a front elevation thereof, and Fig. 3 is a side elevation.

In the casing illustrated, A designates a rectangular base-section having the upwardly-extending and inwardly-sloping sides B and front C, the sides, as shown, merging into the walls of a hollow cylindrical section D. The longitudinal axis of the latter section, as illustrated, lies parallel with the base, while its

15 front end is ring-shaped in form and is beveled to incline inwardly, as shown. Rising from the cylindrical section is the top or cap section E, having formed in the front of its

base portion a rectangular opening G. The front F of the cap or top is convex in form, 25 is ornamented, as shown, and is surmounted by a vertical plate H.

The leading feature of the design consists in the rectangular base-section A, having upwardly-extending and inwardly-sloping sides 30 and front, the hollow cylindrical section D, as shown, arranged with its longitudinal axis in parallelism with the base, and a cap-section E, rising from the cylindrical section, as illustrated, and provided with the convex 35 front F.

What I claim as my invention is—

The design for a casing for vending-machines, substantially as herein shown and described.

In testimony whereof I affix my signature in presence of two witnesses.

WILLIAM C. MURDOCK.
